UNITED STATES PATENT OFFICE.

DANIEL HERBERT SCHWEYER, OF EASTON, PENNSYLVANIA.

TRAIN-STOPPING APPARATUS.

1,279,454.

Specification of Letters Patent. Patented Sept. 17, 1918.

Application filed February 9, 1915. Serial No. 7,074.

To all whom it may concern:

Be it known that I, DANIEL HERBERT SCHWEYER, a citizen of the United States of America, residing at Easton, in the 5 county of Northampton and State of Pennsylvania, have invented new and useful Improvements in Train-Stopping Apparatus, of which the following is a specification.

This invention relates to improvements in 10 train stopping apparatus and has particular application to electrically controlled train stopping mechanism.

In carrying out the present invention, it is 15 my purpose to provide train stopping apparatus whereby a service application of the brakes will be effected, communication between the main air reservoir and the train line air pipe cut off and the propelling power of the train cut down in the event of 20 such train running by a caution signal above a predetermined speed.

It is also my purpose to provide apparatus of the class described whereby an emergency application of the brakes will be brought 25 about and the propelling power of the motor car cut off in the event of the train passing a danger signal.

A further object of my invention is the 30 provision of train stopping apparatus whereby the propelling power of the train will be cut off and the brakes applied in the event of defect in the stopping mechanism.

With the above and other objects in view, the invention consists in the construction, 35 combination and arrangement of parts hereinafter set forth in and falling within the scope of the claims.

In the accompanying drawings;

Figure 1 is a diagrammatic view of the 40 electric circuits employed in my apparatus showing the electroresponsive devices in the positions they occupy when the adjacent road signal is in clear position.

Fig. 2 is a diagrammatic view of the 45 electrically controlled fluid operated mechanism controlling the brakes and the power supply of the train, parts being shown in section.

Fig. 3 is an enlarged vertical sectional view through the speed controlled governor 50 and valve controlled thereby.

Fig. 4 is an enlarged sectional view 55 through the valve controlling the propelling power of the motor car and the electroresponsive device for actuating such valve.

Fig. 5 is a diagrammatic view of a detail 60 of the invention.

Fig. 6 is a detail view of the triple valve. Referring now to the drawings in detail, 1 designates a horizontal cylinder mounted upon an appropriate support carried by the 60 motor car, while 2 indicates a piston capable of sliding movement within the cylinder and provided with a piston rod 3 extending outwardly of one end of the cylinder 1. Disposed adjacent to the outer end of the piston rod 3 is a cylinder 4 of a diameter less than that of the cylinder 1 and slidably mounted within the cylinder 4 is a piston 5 having the piston rod thereof projecting outwardly through one end of the cylinder 70 4 and connected to the piston rod 3 of the piston 2 in the cylinder 1. Located at the opposite end of the cylinder 1 and spaced apart therefrom a suitable distance is a cylinder 6 of a length equal to approximately one-half the length of the cylinder 1 and of a diameter equal to that of the cylinder 1 and slidably mounted within the cylinder 6 is a piston 7 provided with a piston rod 8 extending outwardly through one end wall of the cylinder 6 toward the adjacent end of the cylinder 1. Formed on the outer end of the piston rod 8 and projecting outwardly therefrom coaxial therewith is a sleeve 9 embracing the adjacent 85 end portion of a rod 10 connected to the piston 2 within the cylinder 1 and extending out through the end wall of said last-named cylinder opposite from the piston rod 3. Mounted upon the cylinders 1 and 6 are 90 valves 11 and 12 respectively, each comprising a vertical casing 13 uprising from the particular cylinder and formed adjacent to the upper end thereof with a cavity 14 and adjacent to the lower end thereof with a cavity 15 communicating with the cavity 14 by way of a vertical passage 16. The upper and lower ends of the passage 16 are formed to provide valve seats 17 and 18 and passed through the passage 16 and capable 95 of vertical sliding movement therein is a stem 19 having the lower end thereof disposed within the cavity 15 and the upper end projecting through the top wall of the cavity 14. Secured upon the stem 19 adjacent to the lower end thereof is a valve disk 20 adapted to engage the seat 18 when the stem is in its uppermost position, while secured to the stem within the cavity 14 is a valve disk 21 adapted to engage the seat 17 100 when the stem is in its lowermost position, the valve disk 20 being disengaged from its 105 110

seat when the disk 21 is brought into engagement with the seat 17 and vice versa. In the present instance, an expansion spring 22 is disposed within the cavity 15 and has 5 the lower end abutting the bottom wall of the cavity and the opposite end in engagement with the adjacent extremity of the stem 19, such spring acting to hold the valve stem normally in elevated position and the 10 disk 20 in engagement with the seat 18. Formed in the casing 13 is a fluid passage 23 having one end opening into the particular cylinder adjacent to one end of the latter and the opposite end in communication with 15 the passage 16. The cavity 14 of each valve, is formed with an exhaust port 24 establishing communication between such cavity and the atmosphere. 25 designates a fluid conducting pipe having one end connected to 20 the main air reservoir of the air brake system of the motor car or train and the opposite extremity opening into one end of the cylinder 4. Leading from the pipe 25 is a branch pipe 26 opening into the cavity 15 25 in the casing 13 of the valve 11 and connected with the branch pipe 26 is a second branch pipe 27 opening into the cavity 15 in the casing of the valve 12.

The valves 11 and 12 are under the control 30 of electroresponsive devices 28 and 29 respectively and, in the present instance, each electroresponsive device comprises an electromagnet 30 disposed upon the upper end of the valve casing 13 concentrically of the 35 upper extremity of the stem 19, and an armature 31 secured to the upper extremity of the stem and disposed within the influence of the pole of the electromagnet. Under 40 normal conditions, the device 28 is energized and the device 29 deenergized. When the electromagnet 30 controlling the valve 13 is energized the stem 19 is depressed against the action of the spring 22, thereby 45 disengaging the valve disk 20 from the seat 18 and engaging the disk 21 with the seat 17. In this movement of the valve disks 50 communication between the fluid end of the cylinder 1 and the atmosphere by way of the passage 23, passage 16, cavity 14 and exhaust port 24 is cut off and communication between the supply pipe 25 and the fluid end of the cylinder 1 established by way of the branch pipe 26, cavity 15 and passages 16 and 23. As the air enters the cylinder 1 the piston 2 55 therein is moved toward the opposite end of the cylinder, thereby moving the piston 5 in the cylinder 4 against the action of the air and drawing the rod 10 to the right, the outer end of the rod 10 moving freely within 60 the sleeve 9. On the other hand, when the electromagnet 30 controlling the valve 12 is energized the stem 19 is lowered, thereby 65 disengaging the disk 20 from the seat 18 and engaging the disk 21 with the seat 17, whereby communication between the fluid

end of the cylinder 7 and the atmosphere, by way of the passages 23 and 16 and the cavity 14 and exhaust port 24 therein, is cut off, and communication between the supply pipe 25 and the fluid end of the cylinder 6 established by way of the branch pipes 26 and 27, 70 the cavity 15 and the passages 16 and 23. As the fluid enters the cylinder 6, the piston 7 therein is moved to the right toward the opposite end of the cylinder, thereby sliding 75 the rod 10 to the right through the medium of the rod 8 and sleeve 9. In the movement of the rod 10 under the action of the piston 7, the pistons 2 and 5 also slide within the respective cylinders against the action 80 of the air on the pistons 5 in the cylinder 4. Owing to the cylinder 6 being of a length equal to one-half the length of the cylinder 1, the rod 10 travels just one-half the distance under the action of the piston 7 that it 85 would under the action of the piston 2. When one or the other of the magnets is deenergized, the particular spring 22 restores the valve stem to normal position, thereby establishing communication between the 90 fluid end of the cylinder and the atmosphere and permitting the piston to be restored to normal position under the action of the restoring device formed by the cylinder 4 and piston 5. 95

32 designates a duplex valve comprising a casing 33 having two bores formed therein and lying parallel with each other and rotatably mounted within one of the bores is a plug 34 formed with a transverse passage 100 35 and a port 36 arranged at an angle to the passage 35 and opening into the latter onto the periphery of the plug, while rotatable in the remaining bore is a plug 37 formed with a diametrical passage 38 adapted, when in 105 one position, to establish communication between ports 39, 40 formed in the wall of the particular bore and, when in another position, to cut off communication between such ports. 41 indicates the train line air 110 pipe or brake pipe of a car or train and connected with the train line air pipe 41 is a branch pipe 42 having the remaining end thereof connected with the port 39 in the valve casing 33, the port 40 in the valve 115 casing opening into the atmosphere. The passage 35 in the valve plug 34 is adapted to register with ports 44 and 45 in one position of the plug, while one end of the passage 35 and the port 36 are designed to register with 120 the port 43 and the port 44 in another position of the plug and when the plug is actuated to still another position the passage 35 and port 36 are out of registration with the respective ports. Tapped onto 125 the supply pipe 25 is a branch pipe 46 leading into the port 44, and leading from the port 45 is a pipe 47, while the port 43 opens into the atmosphere. The valve plugs 34 and 37 are connected to each 130

other for simultaneous movement and when the diametrical passage 38 in the plug 37 is in position to establish communication between the ports 39 and 40, the plug 34 is in the neutral or inactive position so that communication between the passage and the port in the plug and the ports in the casing is cut off, while when the plug 34 is in one or the other of its open positions, the plug 37 is in closed position.

48 indicates a valve identical in construction to the valves 11, 12 hereinbefore described and mounted upon the upper end of the casing 13' of the valve 48 is a cylinder 49 into which the upper end of the stem 19 projects and connected to the upper end of the stem 19' within the cylinder 49 is a piston 50, while encircling that portion of the valve stem within the cylinder 49 is an expansion spring 51 having one end in engagement with the under surface of the piston and the opposite end abutting the bottom wall of the cylinder. Tapped into the upper end of the cylinder 49 is the pipe 47. Leading from the train pipe 41 is a branch pipe 52 having the free end thereof opening into the cavity 14' in the casing of the valve 48 and connected with the passage 23' in the casing of the valve 48, by way of a pipe 53, is one port of a triple valve 54, the cavity 15' in the casing 13' of the valve 48 opening into the atmosphere by way of a port 55. A second port of the triple valve 54 is connected with an auxiliary air reservoir 56, while from one of the remaining ports of the triple valve 54 leads a branch pipe 57 connected with the branch pipe 52 and from the remaining port leads a pipe 58. 59 designates a speed controlled valve comprising a substantially rectangular casing 60 having a valve seat 61 formed therein approximately centrally thereof and dividing the casing into upper and lower chambers. Mounted upon the casing 60 of the speed controlled valve 59 is a supporting frame 62 and projecting upwardly from the supporting frame 62 are supporting arms 63, 63 spaced apart and pivoted to the arms 63, 63 are levers 64, 64 respectively extending in opposite directions and having the outer ends thereof equipped with weights 65 and the inner ends working within an annular groove 66 formed in a collar 67 fast upon the upper end of a stem 68 extending downwardly through the frame 62 and the top wall of the casing 60 into the bottom chamber of the casing. The lower end of the stem 68 is provided with a valve disk 69 movable into and out of engagement with the seat 61 and normally held in engagement with such seat by means of a spring 70 encircling the stem 68 and holding the latter in elevated position. In the present instance, the stem 68 is formed of axially aligning sections and the upper section is con-

nected with the lower section through the 65 medium of a swivel joint and capable of rotation and keyed upon the upper section is a bevel pinion 71 meshing with a similar pinion 72 fixed upon one end of a shaft 73 journaled in the supporting frame 62, while 70 secured to the remaining end of the shaft 73 is a bevel pinion 74 meshing with a like pinion 75 fastened to the upper end of a vertical shaft 76, the latter having driving connections 77 with one of the axles of the motor 75 car. 78 designates a valve identical in construction to the valves 11, 12 and 48. This valve 78 is inverted with respect to the valve 48 and secured to the lower end of the casing of the valve 78 is a cylinder 79 into which 80 the lower end of the stem 19' projects and fixed to the end of the stem 19' within the cylinder 79 is a piston 80, while encircling that portion of the stem 19' within the cylinder is a coiled expansion spring 81 having 85 one end in engagement with the upper surface of the piston and the opposite extremity abutting the top wall of the cylinder 79. The lower end portion of the cylinder 80 is in open communication with the upper chamber in the valve casing 60 by way of a pipe 82, while the cavity 15' in the casing of the valve 78 is in open communication with the supply pipe 25 by way of a branch pipe 83 tapped onto the branch pipe 46. 84 designates a cylinder in which is slidably mounted a piston 85 and one end of the cylinder 84 is in open communication with the passage 23 in the casing of the valve 78 by way of a pipe 86. The engineer's brake valve 87 100 has one port thereof connected with the supply pipe 25 as usual and located in the connection between the engineer's brake valve and the supply pipe 25 is a valve 88 normally held in open position and capable of 105 movement to closed position and having the stem thereof connected with the piston 85 in the cylinder 84, an expansion spring 89 encircling that portion of the stem of the valve 88 within the cylinder 84 and having one end in engagement with the adjacent face of the piston 85 and the opposite end abutting the casing of the valve, such spring acting to hold the valve normally open. The cavity 14 in the casing of the valve 78 opens into the 110 atmosphere by way of an exhaust port 90.

The governor composed of the levers 64, weights 65, collar 67 and the upper section of the stem 68 is capable of adjustment and is designed to move the valve disk 59 away 115 from the seat 61 when the train exceeds a predetermined speed. For instance, should the governor be set to open the valve when the train was running above ten miles an hour the weights 65 will fly outwardly under the action of centrifugal force, thereby swinging the levers 64 about their pivotal connections with the arms 63 with the effect

to depress the stem 68 and disengage the valve disk 69 from the seat 61 whereby communication between the upper and lower chambers in the casing 60 is established.

5 When the valve plug 34 is rotated to bring the passage 35 into registration with the ports 44 and 45, communication is established between the supply pipe 25 and the upper end of the cylinder 49 by way of the branch pipe 46, passage 35 in the plug 34 and pipe 47. As the air enters the upper end of the cylinder 49 the piston 50 therein is moved downwardly against the action of the spring 51, thereby moving the valve disk 20' of the valve 48 out of engagement with the seat 18 and engaging the valve disk 21 with the seat 17'. In this position of the disks of the valve 48 communication between the train line air pipe 41 and the 10 triple valve 54 by way of the branch pipe 52, cavity 14', passages 16' and 23' and pipe 53 is cut off and communication between the triple valve and the atmosphere established by way of the pipe 53, passages 23' and 16', 15 cavity 15' in the casing of the valve 48 and exhaust port 55 in said cavity. As the particular port of the triple valve empties into the atmosphere the valve is actuated under the action of the air in the auxiliary reservoir 20 voir 56 to establish communication between the pipes 57 and 58 whereby the air from the train line passes into the lower chamber of the casing of the valve 59 and, should the valve 69 be out of engagement with the seat 25 61, incident to the train traveling above the predetermined speed, the air from the train line pipe will pass through the casing 60, pipe 82 and into the lower end of the cylinder 79, thereby elevating the piston 80 to 30 move the disk 21' of the valve 78 into engagement with the seat 17' and disengage the valve disk 20' from the seat 18'. In this operation of the valve 78, communication is established between the cylinder 84 and 35 the supply pipe 25 by way of the branch pipe 83, cavity 15' in the casing of the valve 78, passages 16' and 23', and pipe 86, so that the piston 85 is actuated within the cylinder 84 against the action of the spring 89 to 40 close the valve 88 and so cut off communication between the main air reservoir and the engineer's brake valve whereby recharging of the train line air pipe is prevented. The cylinder 79 is provided with an exhaust port 91 disposed a short distance from the 45 lower end thereof and designed to be uncovered by the piston 80 and as the latter is elevated under the action of the air from the train line air pipe and when the port 91 is 50 uncovered by said piston the air from the train line air pipe discharges into the atmosphere, thereby bringing about a service application of the brakes. When the speed of the train drops below the prescribed limit 55 determined by the tension of the spring 68

and the weighted arms 64, the valve 59 moves into engagement with its seat, thereby cutting off communication between the brake pipe and the atmosphere and releasing the brakes.

On the other hand, should the train be traveling below the predetermined speed, the valve disk 69 will remain in engagement with the seat 61 and so prevent the reduction of pressure in the train line air pipe.

When the plug 34 is rotated to bring the port 36 into registration with the port 45 and the passage 35 into registration with the port 43, communication between the pipe 46 and the pipe 47 is cut off and communication 80 between the pipe 47 and the atmosphere established whereby the air within the cylinder 49 is exhausted to the atmosphere and the valve 48 restored to closed position by means of the springs 51 and 22. As the valve 48 85 is restored to normal position, the atmospheric port of the triple valve 54 is closed, incident to the valve disk 20' cutting off communication between the exhaust port 55 and the passage 23'. The atmospheric port 90 of the triple valve is now placed in communication with the train line air pipe by way of the branch pipe 52, cavity 14' in the casing of the valve 48, passages 16' and 23' and pipe 53 and as the pressure above the 95 equalizing piston in triple valve 54 is greater than the pressure in the pipe 57 below such piston, the parts of the triple valve are restored to normal position, thereby cutting off communication between the train line air 100 pipe and the valve 59. As the pressure is released from the cylinder 79, the spring 81 restores the valve 78 to normal position, thereby cutting off communication between the supply pipe 25 and the cylinder 84 and 105 placing the rear end of the cylinder 84 in communication with the atmosphere by way of the pipe 86, passages 23' and 16' in the casing of the valve 78, cavity 14' and exhaust port 90. As the pressure is released 110 from the cylinder 84 the spring 89 reacts to open the valve 88 and reestablish communication between the supply pipe 25 and the engineer's brake valve.

To effect an emergency application of the 115 brakes, the valve plugs 34 and 37 are operated to carry the passage and port in the plug 34 out of registration with the respective ports in the casing and to bring the passage 38 in the plug 37 into registration 120 with the ports 39 and 40. When the plug 37 is in this position the train line 41 bleeds directly into the atmosphere. Depending from the interconnected stems of the plugs 34 and 38 is an operating lever 92 connected 125 through the medium of a link 93 with one end of a lever 94 fulcrumed between its ends as at 95 and having the remaining end thereof connected through the medium of a pin and slot connection 96 with the rod 10. 130

When the magnet 28 controlling the valve 11 is energized, the cylinder 1 is in communication with the supply pipe 25 as previously described and the piston 2 slid within the cylinder 1. In the movement of the piston 2 under the action of the incoming air, the rod 10 swings the lever 94 with the effect to rotate the plug 34 to bring the port 36 into registration with the port 45 and the passage 35 into alignment with the port 43. On the contrary, when the magnet controlling the valve 11 is deenergized and the magnet 30 controlling the valve 12 energized the piston 7 in the cylinder 6 is moved through a distance equal to one-half of the path of movement of the piston 2 and in the movement of the piston 7 the rod 10 is actuated to swing the lever 94 about its pivot 95 and rotate the plug 34 to bring the passage 35 into registration with the ports 44 and 45, thereby placing the pipe 46 in communication with the pipe 47 to effect a service application of the brakes, as previously described, in the event of the train running above a predetermined speed when the valve 12 is so actuated. When the magnets controlling both valves 11 and 12 are deenergized, the air is exhausted from both cylinders 1 and 6 as hereinbefore described and the restoring device composed of the cylinder 4 and piston 5 slides the pistons 2 and 7 toward the fluid ends of the respective cylinders. In this movement of the piston 2 the lever 94 is swung in the reverse direction and the valve plug 34 actuated to move the passage and port therein out of registration with the respective ports in the casing, while the plug 37 is rotated to bring the passage 38 into registration with the ports 39 and 40, thereby bringing about an emergency application of the brakes.

In the present embodiment of my invention, I have shown the apparatus as installed in a steam driven locomotive and in order that the propelling power of the locomotive may be cut off automatically upon an emergency application of the brakes, a valve 97 of some suitable construction is located in the steam main 98 leading from the steam space of the boiler to the drive cylinders of the engine. This valve 97 is capable of sliding movement to open and closed positions and is normally in open position and provided with a stem 99 having the outer end thereof equipped with a head 100 disposed within an elongated recess 101 formed in a block 102 fast upon one end of a rod 103, the remaining end of the rod 103 being appropriately connected with the rod 10. The head 100 and the recess 101 in the block 102 form a loose connection between the rod 103 and the stem of the valve 97 so that the valve 97 will remain uninfluenced by the rod 10 in the operation of the latter to service and release positions. When, how-

ever, the rod 10 is operated to emergency position a pull is exerted upon the rod 103 and the stem of the valve 97, and the latter moved to closed position.

If desired, the valve 97 may also be speed controlled so that the same will be actuated to cut down the flow of steam to the drive cylinders of the engine when the latter runs by a caution signal above the predetermined speed. In the present instance, this speed controlled mechanism comprises an electric generator 104 and the solenoid 105 having the terminals thereof connected with the respective sides of the generator through the medium of conductors 106. Movable into and out of the solenoid 105 is a core 107 encircling a rod 108 passed through the solenoid and having one end thereof pivotally connected with a lever 109 pivoted for swinging movement between its ends as at 110 and having the remaining end thereof connected through a pin and slot connection 111 with the stem of the valve 97. Fastened to the opposite end of the rod 108 is a collar 112, while fixed to a suitable support and encircling the rod 108 between the collar 112 and the confronting end of the solenoid 105 is a bearing plate 113. Interposed between the confronting faces of the collar 112 and the bearing plate 113 is a coiled expansion spring 114 acting to hold the core 107 normally withdrawn from the solenoid 105. The generator 104 is suitably connected with one of the axles of the locomotive and when the latter exceeds a prescribed speed determined by the adjustment of the spring 114, the current developed by the generator is sufficient to energize the solenoid 105 so that the latter may draw the armature 107 thereto against the action of the spring 114, thereby swinging the lever 109 and actuating the valve 97 to cut down the flow of steam from the boiler to the drive cylinders of the engine. Located in one of the conductors 106 is a switch 115 whereby the circuit may be normally broken and closed under caution conditions.

Located upon one side of the lines of rails of the trackway and spaced apart longitudinally thereof and disposed adjacent to the respective signals are contact rails 116 each connected by way of a wire 117 and a switch 118 with the adjacent line of rails of the trackway, while disposed at the opposite side of the lines of rails and spaced apart longitudinally thereof and arranged adjacent to the signals respectively are contact rails 119, each connected by way of a wire 120 and a switch 121 with the adjacent line of rails. The contact rails 119 are preferably spaced apart longitudinally from the contact rails 116 respectively so that such contact rails will alternate.

Located upon one side of the locomotive and co-operating with the ramp rail or con-

tact rail 116 is a controlling switch 122 comprising a vertical stem 123 mounted within a bearing 124 and capable of vertical sliding movement. Secured to the lower end 5 of the stem 123 is a shoe 125 adapted to ride upon the ramp rail 116 and as the shoe rides over the upper surface of the ramp rail the stem 123 is elevated, while when the shoe is relieved of the influence of the 10 rail, such shoe and stem are lowered. Disposed adjacent to the stem 123 and spaced apart vertically are contacts 126, 127 and 128. Fast to the stem 123 and spaced apart vertically thereon are contacts 129, 130 15 adapted to engage the contacts 126 and 127 respectively when the stem is in lowered position, and fastened to the stem above the contact 130 is a contact 131 adapted to engage the contact 128 when the stem is in 20 elevated position and the contacts 129, 130 out of engagement with the contacts 126, 127. In the present instance, an expansion spring 132 surrounds the stem 123 and has one end thereof bearing against the contact 130 and the opposite end abutting the bearing 124, such spring acting to hold the stem in lowered position normally. Secured to the opposite side of the locomotive and depending therefrom and coöperating with 25 the ramp rail 119 are controlling switches 133, 134. In the present instance, the switch 133 comprises a vertical stem 135 mounted within a suitable bearing and capable of vertical sliding movement. Secured to the lower end of the stem 135 is a shoe 136 adapted to ride upon the ramp rail 119 and as the shoe rides over the ramp rail the stem is elevated, while when the shoe leaves the ramp rail the stem and shoe are 30 lowered. Disposed adjacent to the stem 135 is a contact 139 and secured to the stem above the contact 139 is a contact 138 engaging the contact 139 when the stem is in lowered position. Secured to the stem 45 135 below the contact 138 is a contact 139 designed to engage the contact 139 when the stem is elevated under the action of the shoe 136 and ramp rail 119. A spring 140 acts to restore the stem and shoe to lowered position succeeding the movement of the shoe off of the ramp rail. In this form of my invention, the controlling switch 134 comprises a stem 141 mounted within a bearing and capable of sliding movement therein 50 and having the lower end thereof equipped with a shoe 142 adapted to engage the ramp rail 119. As the shoe 142 rides over the ramp rail 119 the stem 141 is elevated while when the shoe leaves the ramp rail the stem and shoe are lowered. Disposed adjacent to the stem 141 is a contact 143 adapted to be 55 engaged by a contact 144 on the stem 141 when the stem is in lowered position, while disposed adjacent to the stem 141 above the contact 143 are contacts 145 spaced apart

about the stem and secured to the stem above the contacts 145 is a contact 146 adapted to bridge the contacts 145 when the stem is in lowered position. 147 designates a spring surrounding the stem 141 and acting upon the latter to hold the same in lowered position and restore the same to such position when the shoe leaves the ramp rail.

Disposed within the locomotive in some convenient location is a base board 148 and 75 suitably secured to the base board 148 are vertically disposed electromagnets 149, 150 and 151 appropriately spaced apart. Disposed below each magnet 149, 150, 151 is a horizontal armature 152 pivoted at one end 80 as it 153. Secured to the upper and lower surfaces of the armature of the magnet 150 adjacent to the free end of such armature are contacts 154, 155 respectively adapted to engage contacts 156 and 157, while secured 85 to the upper surface of the armature of the magnet 149 adjacent to the free end of such armature is a contact 158 normally in engagement with a contact 159, while fastened to the end of the armature of the magnet 90 149 and insulated therefrom and disposed in the same plane as the armature is a strip 160 and secured to the upper and lower surfaces of the strip 160 are bridging plates 161, 162 respectively. The bridging plate 95 161 is adapted to bridge contacts 163, while the plate 162 is designed to bridge the contacts 164. Secured to the upper surface of the armature of the magnet 151 adjacent to the end of such armature remote from 100 the pivot point thereof is a contact 165 adapted to engage a contact 166 and secured to such end of the armature and insulated therefrom is a strip 167 disposed in the same plane as the armature and having the 105 under surface thereof equipped with a bridging strip 168 adapted to engage contacts 169. When the magnets 149, 150 and 151 are energized the respective armatures are held in elevated position against the 110 pole faces of the magnets and the contact 154 on the armature of the magnet 150 engages the contact 156, while the contacts 158 and 165 on the upper surfaces of the armatures of the magnets 149, 151 respectively 115 engage the respective contacts 159 and 166. In the elevated position of the armature of the magnet 149 the bridging plate 161 bridges the contacts 163. On the other hand, when said magnets are deenergized 120 the armature 152 of the magnet 150 drops and the contact 155 engages the contact 157, and the armatures of the magnets 149 and 151 respectively drop so that the bridging plate 162 connected to the armature of the 125 magnet 149 bridges the contacts 164, while the bridging strip 168 connected to the armature of the magnet 151 bridges the contacts 169. Mounted upon the base board 148 and appropriately fastened thereto are 130

caution, clear and danger signal lamps 170, 171, 172 colored green, white and red respectively, while secured to the base board is a manually operable switch 173 comprising a blade 174 pivoted at one end as at 175 for swinging movement and adapted to be moved into engagement with a contact 176 and normally engaging a contact 177 under the action of a spring 178, the blade 10 being operable manually to disengage the contact 177 and engage the contact 176 against the action of the spring 178, the latter acting to restore the blade to engagement with the contact 177 when the pressure 15 sure on the blade is released.

In the present instance, the stem 123 of the controlling switch 122 is formed of upper sections carrying the contacts 130, 131 respectively and a lower section carrying the contact 129 and the meeting ends of these sections are suitably fastened to each other and insulated from each other. Likewise, the stem 141 of the switch 184 is formed of two sections insulated one from 25 the other and the upper section carries the contact 146 while the lower section carries the contact 144.

Suitably located upon the locomotive or motor car is a source of electrical energy 30 which, in the present instance, is in the form of a battery 179. Leading from one side of the battery 179 is a conductor 180 terminally connected with one end of a conductor 181 and the remaining terminal of the conductor 181 is connected to the lower section 35 of the stem 123 of the switch 122. The contact 129 on the lower section of the stem 123 is electrically connected with the shoe 125 by means of a wire 182. From the contact 40 126 leads a conductor 183 terminally connected to the lower section of the stem 141 of the controlling switch 134, while the contact 144 on the lower section of said stem is electrically connected with the shoe 142 by way of 45 a wire 184. From the contact 143 of the switch 134 leads a conductor 185 terminally connected to the armature 152 of the electro-magnet 149. Connected to the contact 159 engaging the contact 158 on the armature of 50 the magnet 149 is a conductor 186 extending through the winding of the magnet 149 and terminally connected with one end of a return conductor 187 terminally connected to the remaining side of the battery 179. 55 By means of this construction, it will be seen that as long as the stems of the respective switches 122 and 134 are in lowered position a circuit including the magnet 149 will be closed, thereby maintaining the magnet 149 energized and the armature 152 in elevated position, current flowing from one side of the battery 179, through the conductors 180, 181, contacts 129 and 126 of the switch 122, conductor 183, contacts 144 and 60 143 of switch 134, conductor 185, armature 65 143 of switch 134, conductor 185, armature

152 of magnet 149, conductor 186, and the winding of the magnet 149 and then back to the other side of the battery by way of the return conductor 187.

187 designates a ground magnet located 70 upon the locomotive and controlling a horizontal armature 188 disposed below the magnet and pivoted at one end and having the opposite end thereof provided with a depending contact 189 normally engaging a 75 contact 190. As long as the magnet 187 remains deenergized, the contact 189 engages the contact 190 while when the magnet is energized the armature 188 is elevated and the contact 189 disengaged from the contact 190. 80

The clear signaling lamp 171 is connected in parallel with the circuit of the magnet 149 by way of a conductor 191 having one terminal connected to the conductor 186 adjacent to the contact 159 and the remaining terminal connected to one side of the lamp 171, and a conductor 192 having one side connected to the remaining terminal of the lamp 171 and the other end connected to the contact 190. From the pivot point of the armature 188 leads a conductor 193 terminally connected with the return wire 187 and forming, in effect, a continuation of the conductor 192 when the contacts 189 and 190 95 are in engagement with each other. Thus, as long as the magnet 149 is energized and 187 is deenergized the clear signal lamp 171 burns to indicate the condition of the apparatus, current flowing from the conductor 100 186, through the conductor 191, the clear signal lamp 171, the conductor 192, contacts 190 and 189, the armature lever 188, conductor 193 and conductor 187, back to the other side of the battery 179. 105

The magnet 151 is connected in shunt with the magnet 149 through the medium of a conductor 194 having one terminal connected to the conductor 186 at one side of the magnet 149 and the remaining end connected to 110 one terminal of the magnet 151, and a conductor 195 having one end connected to the remaining terminal of the magnet 151 and the opposite terminal connected to the conductor 186 at the other side of the magnet 115 149. Thus, as long as the magnet 149 is energized the magnet 151 is likewise affected and holds the armature 152 elevated and the contacts 165 and 166 in engagement with each other, current flowing from the conductor 186 at one side of the magnet 149, through the conductor 194, the magnet 151, and the conductor 195, back to the conductor 186 at the other side of the magnet 149. The magnet 151 controls the circuit of the 120 magnet 150 and this circuit comprises a conductor 196 having one terminal connected to the conductor 180 and the remaining end connected to the pivot point of the armature 152 of the magnet 151, a conductor 197 hav- 125 130

ing one end connected with the contact 166 and the remaining end connected to one terminal of the magnet 150, a conductor 198 having one end connected to the remaining terminal of the magnet 150 and the opposite end connected to the contact 138 on the upper section of the stem 135 of the switch 133, and a conductor 199 having one terminal connected to the contact 137 of the switch 133 and the opposite terminal tapped onto the return conductor 187. From this it will be seen that as long as the magnet 151 is energized and the armature 152 thereof held in elevated position and the stem of the switch 133 lowered, the circuit of the magnet 150 will be closed and current flow from one side of the battery 179, through the conductor 180, conductor 196, armature 152, of magnet 151, conductor 197, magnet 150, conductor 198, contact 138 of switch 133, contact 137 engaged by contact 138, conductor 199, and back to the battery by way of conductor 187.

The electroresponsive device 28 is also connected in parallel with the circuit of the magnet 149 and therefore normally energized. In the present instance, the connections between the electroresponsive device 28 and the circuit of the magnet 149 comprise a conductor section 200 having one end connected to the conductor 195 adjacent to the connection between such conductor and the conductor 186 and the remaining terminal connected to one of the contacts 163, a conductor 201 having one terminal connected to the remaining contact 163 and the other end connected to one terminal of the electroresponsive device 28, and a conductor 202 having one end connected to the remaining end of the electroresponsive device 28 and the opposite end tapped onto the conductor 192. Thus, the electroresponsive device 28 is normally energized and maintained in such condition as long as the magnet 149 is energized and the bridging strip 161 in engagement with the contacts 163, current flowing from the conductor 195, through the conductor 200, contacts 163 and bridging strip 161, conductor 201, electroresponsive device 28, conductor 202, a portion of the conductor 192, the contacts 190 and 189, armature lever 188, and the conductors 193 and 187 to the other side of the battery.

The caution signal lamp 170 and the electroresponsive device 29 are connected in circuit with the battery 179 and in parallel with each other and are controlled by the switch composed of the contacts 164 and the bridging plate 162 under the control of the armature of the magnet 149 so that when the magnet 149 is deenergized and the armature 152 thereof lowered the caution signal lamp 170 will be energized and the electroresponsive device similarly affected. In this

instance, one side of the caution signal lamp 170 is connected by way of a conductor 203 with the conductor 194, while leading from the remaining side of the caution signal lamp is a conductor 204 terminally connected to one of the contacts 164 and from the other contact 164 leads a conductor 205 terminally connected to the conductor 197. Tapped onto the conductor 204 is a conductor 206 connected to one terminal of the winding of the electroresponsive device 29 and from the remaining terminal of said electroresponsive device leads a conductor 207 tapped onto the conductor 193. A conductor 208 has one terminal tapped onto the conductor 180 and the remaining terminal connected with the pivot point 153 of the armature 152 of the magnet 150, while a conductor section 209 forms a connection between the contact 156 and the conductor 197. By means of these connections, it will be seen that when the armature 152 of the magnet 149 is in lowered position and the contacts 164 bridged by the plate 162, current will flow from one side of the battery 179, through the conductor 180, conductor 208, armature of magnet 150, contacts 154 and 156, conductors 209 and 205, contacts 164 and plate 162, conductor 204, lamp 170, conductor 203, conductor 186, and back to the battery by way of the return conductor 187. Simultaneously, current flows from the conductor 204, through the conductor 206, electroresponsive device 29, conductor 207, and conductor 193 connected to conductor 187. Thus, the caution signal lamp is energized and the electroresponsive device 29 energized. As the contact 156 included in the circuit of the lamp 170 is connected to the conductor 209, a holding circuit for the magnet 150 is established, the current in this holding circuit flowing from one side of the battery 179, through the conductors 180 and 208, armature 152, of magnet 150, contacts 154 and 156, a portion of the conductor 197, winding of magnet 150, conductor 198, contacts 138 and 137 of switch 133, conductor 199, and back to the battery by way of return conductor 187. Thus, the magnet 150 is maintained energized and the armature 152 thereof elevated to hold the caution signal lamp and the electroresponsive device 29 energized during deenergization of 149.

Leading from the contact 157 is a conductor 210 connected to one side of the danger signal lamp 172 and from the remaining side of the lamp 172 leads a conductor 211 terminally connected to the return conductor 187. When the magnet 150 is deenergized and the armature 152 thereof in lowered position the contact 155 engages the companion contact 157 and so closes a circuit through the danger signal lamp 172, current flowing from one side of the battery 179, through the conductors 180 and 130.

208, armature 152, contacts 155, 157, conductor 210, lamp 172, conductor 211, and return conductor 187.

In the present instance, a ground wire 212 has one terminal grounded upon one of the axles and wheels of the motor car and the remaining terminal connected to the conductor 195 and connected in the ground conductor is a ground signal lamp 213 and conductor 10 connected in shunt with the signal lamp 213 by way of conductor 214, 215 is the ground magnet 187.

In practice, when the shoe 125 rides over a ramp rail 116 with switch 118 open the contact 129 is disengaged from the contact 126 with the effect to break the circuit of the magnet 149 and so energize the caution signal lamp 170 and the electroresponsive device 29 and deenergize the electroresponsive device 28, whereby a service application of the brakes will be brought about as hereinbefore described. When, however, the switch 118 is closed, the break in the circuit of the magnet 149 will be bridged and current flow from the contact 129, through the wire 182, shoe 125, ramp rail 116, switch 118, track rail and wheels and axle of the motor car, ground conductor 212, and conductor 195, through the magnet 149, back 25 to the battery. Thus, the magnet 149, magnet 151 and lamp 171 will be maintained energized, the electroresponsive device 28 held energized and the similar device 29 maintained deenergized. On the other hand, should the switch 118 be open the circuit of the magnet 149 will be broken and the apparatus placed in operation to effect a service application of the brakes and check the speed of the car or train.

40 When the shoes 136 and 142 on the lower ends of the stems of the switches 133 and 134 respectively ride over a danger ramp rail 119 the contacts 138 and 144 of the respective switches disengage the contacts 137 and 143. As the contact 144 of the switch 134 disengages the contact 143 the electrical connection between the conductors 183 and 185 is broken with the effect to deenergize the magnet 149; but, when the switch 121 is closed a ground path is established and the magnet 149 maintained energized, current flowing from the conductor 183; through the contact 144; wire 184, shoe 142, ramp rail 119, switch 121, track rail, wheels and axle 50 of a car, ground conductor 212, conductor 195, conductor 186, magnet 149, and back to the other side of the battery. Thus, the magnet 149, magnet 151, lamp 171 and electroresponsive device 28 are maintained energized. When, however, the switch 121 is open, this circuit is broken and the magnets 149, 151, lamp 171 and electroresponsive device 28 deenergized. When the contact 138 of the switch 133 disengages the contact 137, the magnet 150 is deenergized and

the armature 152 drops to close the circuit through the red lamp 172, thereby indicating to the motorman or engineer that a danger signal is being passed. When the switch 121 is closed, the magnet 150 is immediately 70 reenergized when the switch 133 is relieved of the influence of the ramp rail, while when the switch 121 is open and the magnet 150 deenergized the circuit of the magnet 150 remains open when the switch 133 is disengaged from the ramp rail 119.

In order to prevent momentary deenergization of the electroresponsive device 28 incident to the energization of the ground magnet 187' and the consequent lifting of 80 the armature 188 when the switches 122 and 134 are actuated by the respective ramp rails and the switches 118 and 121 closed, suitable means is provided. In the present instance, a conductor 216 has one terminal connected to the conductor 202 and the opposite terminal connected to the contact 131 of the switch 122, while leading from the contact 128 of such switch is a wire 217 terminally connected with the return wire 187. By 85 means of these connections, it will be seen that when the stem of the switch 122 is elevated and the contact 131 engaged with the contact 128 a path around the contacts 189 and 190 will be established so that the 90 electroresponsive device 28 will remain energized irrespective of the lifting of the armature 188 under the action of the energized magnet 187', current flowing from the conductor 202, through the conductor 216, contacts 128 and the contact strip 131, and the conductor 217 to the conductor 187. Tapped onto the conductor 216 is a conductor 218 terminally connected with the shoe 136 of the controlling switch 133: 105 When the shoe 136 of the switch 133 is elevated under the action of the ramp rail 119, the contact 139 abuts against the contact 137 and so establishes an auxiliary circuit for the electroresponsive device 28 to maintain 110 the latter energized when the switches 133 and 134 are actuated by the ramp rail and the switch 121 in closed position, current flowing from the conductor 202, through a portion of the conductor 16, the conductor 218, the shoe 136, the contacts 139 and 137, and the conductor 199 to the common return conductor 187. The contact 139 is preferably insulated from the contact 138 in some suitable manner as, for instance, by forming the stem 135 of two sections carrying respectively the contacts 138 and 139.

Disposed below the armatures 152, of the respective magnets 149, 151 and preferably of greater strength than the magnets 149, 151 are electromagnets 219, connected in parallel in an electric circuit including a conductor 220 having one terminal fastened to the contact 177 of the switch 173 and the remaining terminal connected to one of the 125 130

contacts 169, a conductor 221 having one end connected to the remaining contact 169 and the opposite terminal connected to the return conductor 187, a conductor 222 having one end connected to the pivot point of the switch blade 174 and the remaining terminal connected to the contact 127 of the controlling switch 122, a conductor 223 having one terminal connected to the contact 130 of the switch 122 and the remaining terminal connected to one of the contacts 145 of the switch 134 and a conductor 224 having one terminal connected to the remaining contact 145 and the opposite terminal connected to the ground wire 212. In the event of grounding of the side of the battery 179 opposite from that adapted to be connected to the ground wire 212, and the consequent deenergizing of the magnets 149, 150 and 151, the magnets 219, will be energized and so pull the armatures 152 of the respective magnets 149, 151 downwardly to bring the train to a stop, current flowing from the grounded side of the battery 179, through the ground wire 212, conductor 224, contacts 146 and 145, conductor 223, contacts 130 and 127, conductor 222, switch blade 174, contact 177, conductor 220 and electromagnets 219, bridged contacts 169 and conductor 221 to return conductor 187. Thus, the armatures of the magnets 149, 151 will be held in lowered position.

The contact 176 of the switch 173 is connected by way of a conductor 225 with the conductor 185 and when the switch blade 174 is swung into engagement with the contact 176, current flows from one side of the battery 179, through the conductors 180 and 181, contacts 129 and 126, conductor 183, contacts 144 and 143, conductor 185, conductor 225, contact 176, blade 174, conductor 222, contacts 127, 130, conductor 223, conductor 224, a portion of the conductor 212, conductor 195, conductor 186, magnet 149 and back to the other side of the battery by way of the return wire 187. Thus, the magnets 149, 151 and 150 are reenergized to restore the apparatus to normal condition and the magnets 219 deenergized.

50 This switch 173 is preferably located upon the tender of the locomotive so that the engineer will be compelled to descend from the locomotive to restore the automatic train stopping apparatus to normal condition succeeding the operation of such apparatus.

For the purpose of economizing in the electrical current consumed by the electroresponsive devices 28 and 29 when energized some suitable means is employed. In the 60 present instance, I have shown in Fig. 5, the electroresponsive device 29 as equipped with a current saving device and as both electroresponsive devices 28 and 29 are similarly equipped it is thought that a description of 65 one will suffice for both. In the present in-

stance, the conductor 207 is split transversely and one of the ends of the split portion secured to a bracket 226 carrying a contact 227. Pivoted upon the bracket 226 is a lever 228 having one end formed with a dog 229 and the opposite end equipped with an armature 230 disposed within the influence of an electromagnet 231 that draws less current than the electroresponsive device 29. This magnet 231 is connected in shunt with the 75 electroresponsive device 29 and connected in the shunt circuit is a circuit closer including a contact 232 secured to the valve stem 19 and insulated therefrom and movable therewith and a stationary contact 233. Secured 80 to the valve stem 19 is a lug 234 adapted to be engaged by the dog 229. Depending from the lever 228 adjacent to the dog 229 is a contact 235 designed to engage the contact 227 and to this contact 235 is secured the 85 remaining end of the split portion of the conductor 207. When the device 29 is initially energized, current flows through the conductor 207 and the bracket 226 and contacts 235 and 227 connected in said conductor. Upon the energization of the electroresponsive device 29 the valve stem is moved longitudinally as previously described and the contact 232 engages the contact 233, thereby closing the shunt circuit and energizing the magnet 231. As the magnet 231 is energized, such magnet attracts the armature 230 and swings the lever 228 about its pivotal connection with the bracket 226, thereby breaking the circuit at the contacts 100 227 and 235 and moving the dog 229 into engagement with the lug 234 whereby the valve stem will be held in actuated position under the action of the magnet 231 independently of the electroresponsive device 29. 105

While I have herein shown and described the preferred form of my invention by way of illustration, I wish it to be understood that I do not limit or confine myself to the precise details of construction herein described and delineated, as modification and variation may be made within the scope of the claims without departing from the spirit of the invention.

I claim:

1. In train stopping apparatus, means for effecting an emergency application of the brakes and normally held inactive, means for effecting a service application of the brakes and normally held inactive, an electroresponsive device controlling said first means, an electroresponsive device controlling said second-named means, a normally closed circuit including said first device, a normally open circuit including said second device, and means for opening said first circuit and closing said second circuit under certain conditions whereby the first device will be deenergized and the second device energized. 115

2. In train stopping apparatus, means for effecting an emergency application of the brakes and normally held inactive, means for effecting a service application of the 5 brakes and normally held inactive, an electroresponsive device controlling said first means, an electroresponsive device controlling said second-named means, a normally closed circuit including said first device, a 10 normally open circuit including said second device, and means for opening said first circuit and maintaining said second circuit open under certain conditions to effect an emergency application of the brakes.
- 15 3. In train stopping apparatus, means for effecting an emergency application of the brakes and normally held inactive, means for effecting a service application of the 15 brakes and normally held inactive, an electroresponsive device controlling said first means, an electroresponsive device controlling said second-named means, a normally closed circuit including said first device, a 20 normally open circuit including said second device, means for opening said first circuit and closing said second circuit under certain 25 conditions whereby the first device will be deenergized and the second device energized, and means for opening said first circuit and maintaining said second circuit open 30 under certain other conditions to effect an emergency application of the brakes.
4. In train stopping apparatus, means for effecting an emergency application of the 35 brakes and normally held inactive, means for effecting a service application of the brakes and normally held inactive, an electroresponsive device controlling said first means, an electroresponsive device controlling 40 said second-named means, a normally closed circuit including said first device, a normally open circuit including said second device, means for opening said first circuit and closing said second circuit under certain 45 conditions whereby the first device will be deenergized and the second device energized, means for opening said first circuit and maintaining said second circuit open under certain other conditions to effect an 50 emergency application of the brakes, and signal lamps connected in circuit with said electroresponsive devices respectively to indicate the condition thereof.
5. In train stopping apparatus, means for effecting an emergency application of the 55 brakes, means for effecting a service application of the brakes, an electroresponsive device controlling said first-named means, an electroresponsive device controlling said 60 second-named means, an electric circuit including said first device, an electric circuit including said second device, means holding said first circuit closed, and means for actuating said last means to open said first 65 circuit and close said second-named circuit. 65
6. In train stopping apparatus, means for effecting an emergency application of the brakes, means for effecting a service application of the brakes, an electroresponsive device controlling said first-named means, 70 an electroresponsive device controlling said second-named means, an electric circuit including said first device, an electric circuit including said second device, means holding said first circuit closed, means for actuating said last means to open said first circuit and close said second-named circuit, and signal lamps connected in circuit with said device respectively to indicate the condition thereof. 75
- 80 7. In train stopping apparatus, means for effecting an emergency application of the brakes, means for effecting a service application of the brakes, an electroresponsive device controlling said first-named means, 85 an electroresponsive device controlling said second-named means, an electric circuit including said first device, an electric circuit including said second device, means controlling both of said circuits, an electroresponsive device holding said means normally in position to close said first circuit, a normally closed electric circuit including said last device, and a controlling switch in said last circuit and operable to open the latter. 90
- 95 8. In train stopping apparatus, means for effecting an emergency application of the brakes, means for effecting a service application of the brakes, an electroresponsive device controlling said first-named means, an electroresponsive device controlling said second-named means, an electric circuit including said first device, an electric circuit including said second device, means controlling both of said circuits, an electroresponsive device holding said means normally in position to close said first circuit, a normally closed electric circuit including said last device, a controlling switch in said last circuit and operable to open the latter, and a track instrument for actuating said switch to open the latter. 100
- 105 9. In train stopping apparatus, means for effecting an emergency application of the brakes, means for effecting a service application of the brakes, an electroresponsive device controlling said first-named means, an electroresponsive device controlling said second-named means, an electric circuit including said first device, an electric circuit including said second device, means controlling both of said circuits, an electroresponsive device holding said means normally in position to close said first circuit, a normally closed electric circuit including said last device, a controlling switch in said last circuit and operable to open the latter, a track instrument for actuating said switch to open the latter, and means for maintaining said 110

- 130

last circuit closed irrespective of the opening of said switch under certain conditions.

10. In train stopping apparatus, means for effecting an emergency application of the brakes, means for effecting a service application of the brakes, an electroresponsive device controlling said first-named means, an electroresponsive device controlling said second-named means, an electric circuit including said first device, an electric circuit including said second device, means controlling both of said circuits, an electroresponsive device holding said means normally in position to close said first circuit, a normally closed electric circuit including said last device, a controlling switch in said last circuit and operable to open the latter, a track instrument for actuating said switch to open the latter, means for maintaining said last circuit closed irrespective of the opening of said switch under certain conditions, and means for actuating said first-named means to open said first circuit in the event of grounding of the source of energy of said last-mentioned circuit.

11. In train stopping apparatus, means for effecting an emergency application of the brakes, means for effecting a service application of the brakes, an electroresponsive device controlling said first-named means, an electroresponsive device controlling said second-named means, an electric circuit including said first device, an electric circuit including said second device, means controlling both of said circuits, an electroresponsive device holding said means normally in position to close said first circuit, a normally closed electric circuit including said last device, a controlling switch in said last circuit and operable to open the latter, a track instrument for actuating said switch to open the latter, means for maintaining said last circuit closed irrespective of the opening of said switch under certain conditions, and means for opening said second-named circuit at a point remote from the closing thereof by said means controlling the circuit of the first-mentioned device.

12. In train stopping apparatus, means for effecting an emergency application of the brakes and normally held inactive, means for effecting a service application of the brakes and normally held inactive, an electroresponsive device controlling said first means, an electroresponsive device controlling said second-named means, a normally closed circuit including said first device, a normally open circuit including said second device, means for opening said first circuit and closing said second circuit under certain conditions whereby the first device will be deenergized and the second device energized, and means associated with each of said electroresponsive devices for cutting the lat-

ter out of service and maintaining the particular brake controlling means in operated position.

13. In train stopping apparatus, a valve connected to the train line air pipe and operable to bleed the latter to bring about an emergency application of the brakes, means controlled from said valve to bring about a service application of the brakes, a fluid motor having an element adapted when unrestrained to operate said valve to effect the first-mentioned result, an electro-mechanical device normally restraining said element from operation, an electro-mechanical device for restraining the operation of said motor to cause said valve to effect the second-mentioned result, and means controlling said devices.

14. In train stopping apparatus, a valve connected to the train line air pipe and operable to bleed the latter to bring about an emergency application of the brakes, means controlled from said valve to bring about a service application of the brakes, a fluid motor having an element adapted for operating said valve to effect the first-mentioned result, said motor further having an element adapted for operating said valve to effect the second-mentioned result, means controlling said elements and means for cutting off communication between the main air reservoir and the train line air pipe in the operation of said valve.

15. In train stopping apparatus, a valve connected to the train line air pipe and operable to bleed the latter to bring about an emergency application of the brakes, means controlled from said valve to bring about a service application of the brakes, a fluid motor having an element adapted for operating said valve to effect the first-mentioned result, said motor further having an element adapted for operating said valve to effect the second-mentioned result, means controlling said elements and speed-controlled means for cutting off communication between the main air reservoir and the train line air pipe in the operation of said valve.

16. In train stopping apparatus, the combination with the steam main of a locomotive, of a valve in said main, automatic means for effecting service and emergency applications of the brakes, and a loose connection between said means and said valve whereby the latter will be uninfluenced by said means in the operation thereof to service position and operated by said means to cut off the flow of steam in the operation of said means to emergency position.

17. In train stopping apparatus, the combination with the steam main of a locomotive, of a valve in said main, automatic means for effecting service and emergency applications of the brakes, a loose connec-

- tion between said means and said valve whereby the latter will be uninfluenced by said means in the operation thereof to service position and operated by said means to 5 cut off the flow of steam in the operation of said means to emergency position, and means for operating said valve to cut down the flow of steam to the drive cylinders of the engine independently of said first means in 10 the operation of said first means to service position.
18. In train stopping apparatus, the combination with the steam main of a locomotive, of a valve in said main, automatic means 15 for effecting service and emergency applications of the brakes, a loose connection between said means and said valve whereby the latter will be uninfluenced by said means in the operation thereof to service position 20 and operated by said means to cut off the flow of steam in the operation of said means to emergency position, and speed controlled means for operating said valve to cut down the flow of steam to the drive cylinders to 25 the engine independently of said first means in the operation of said first means to service position.
19. In train stopping apparatus, the combination with the controlling element of a 30 motor car, of automatic means for effecting service and emergency applications of the brakes, and a loose connection between said means and said controlling element whereby the latter will be uninfluenced by said means 35 in the operation thereof to service position and operated by said means to cut off the propelling power of the motor car in the operation of said means to emergency position.
20. In train stopping apparatus, the combination with the controlling element of a 40 motor car, of automatic means for effecting service and emergency applications of the brakes, a loose connection between said means and said controlling element whereby the 45 latter will be uninfluenced by said means in the operation thereof to service position and operated by said means to cut off the propelling power of the motor car in the operation of said means to emergency position,
- 50 and speed controlled means for operating said controller to cut down the motive power of the car independently of said first-named means in the operation of said first-named means to service position.
- 55 21. In train controlling apparatus, the combination with the brake pipe, of a mechanism for establishing connection between the brake pipe and the atmosphere; said mechanism including a valve adapted to be 60 operated by fluid pressure, a source of fluid supply for said valve, and means operative under certain conditions for establishing connection between said source and said valve; said mechanism further including a speed controlled valve having connection 65 with the first-mentioned valve whereby said mechanism will be rendered inoperative below a predetermined speed.
22. In train controlling apparatus, the combination with the brake pipe, and the 70 fluid supply pipe, of a valve for establishing connection between said brake pipe and supply pipe, and a mechanism for establishing connection between said brake pipe and the atmosphere, said mechanism including a 75 valve adapted to be opened under certain conditions of the trackway of the train, and a valve controlled by the speed of the train; the first-mentioned valve having means whereby it will be closed in an operative 80 condition of said mechanism and will be opened in an inoperative condition of said mechanism.
23. In train stopping apparatus, means 85 for effecting a service application of the brakes, and an emergency application of the brakes, means acting normally to actuate said first means to emergency position, means holding said second means normally against operation and adapted to release the same, and means adapted to check the operation of said second-named means upon the release of said holding means to hold said first means in service position.
24. In train stopping apparatus, means 90 for effecting a service application of the brakes, and an emergency application of the brakes, means acting normally to actuate said first means to emergency position, means holding said second means normally 95 against operation and adapted to release the same, means adapted to check the operation of said second-named means upon the release of said holding means to hold said first means in service position, and electroresponsive devices controlling said second and last-named means respectively.
25. In train stopping apparatus, means 100 for effecting a service application of the brakes, and an emergency application of the brakes, means acting normally to actuate said first means to emergency position, means holding said second means normally 105 against operation and adapted to release the same, means adapted to check the operation of said second-named means upon the release of said holding means to hold said first means in service position, electroresponsive devices controlling said second and last-named means respectively, 110 115
26. In train stopping apparatus, means for effecting a service application of the brakes, and an emergency application of the brakes, a fluid motor acting normally to actuate said first means to emergency position.

tion, a fluid motor holding said first motor normally against operation and adapted to release the same, and a fluid motor adapted to check the operation of said first motor 5 upon the release of the same by said holding motor to hold said first-named means in service position.

27. In train stopping apparatus, means for effecting a service application of the 10 brakes, and an emergency application of the brakes, a fluid motor acting normally to actuate said first means to emergency position, a fluid motor holding said first motor normally against operation and adapted to release the same, a fluid motor adapted to 15 check the operation of said first motor upon the release of the same by said holding motor to hold said first-named means in service position, valves controlling said second and 20 last-named motors respectively, and electro-responsive devices controlling said valves.

28. In train stopping apparatus, the combination with the brake pipe, means for establishing communication between said pipe 25 and the atmosphere, a speed controlled valve controlling communication between said means and pipe and operable when the train is traveling above a predetermined speed to establish communication between said pipe 30 and means, and means controlling communication between said brake pipe and said speed controlled valve and operable to open position under conditions other than speed whereby the pressure in the brake pipe may 35 be reduced when said first means is open.

29. In train controlling apparatus, the combination with the brake pipe and supply pipe of a valve connected to said pipes and normally operable to charge said brake pipe, 40 a second valve connected to said brake pipe, means operable under certain conditions to actuate said second valve to produce an emergency application of the brakes, means operable under other conditions to actuate 45 said second valve to produce a service application of the brakes, and means connected to said second valve whereby when one of said applications of the brakes is produced the first mentioned valve will be rendered inoperable to charge the brake pipe.

30. In train controlling apparatus, the combination with the brake pipe and supply

pipe of a valve connected to said pipes and normally operable to charge said brake pipe, 55 a second valve connected to said brake pipe, means operable under certain conditions to actuate said second valve to produce an emergency application of the brakes, means operable under other conditions to actuate said second valve to produce a service application 60 of the brakes, means connected to said second valve whereby when one of said applications of the brakes is produced the first mentioned valve will be rendered inoperable to charge the brake pipe, and speed-controlled 65 means governing the operation of said second valve to produce a service application of the brakes.

31. In train controlling apparatus, a mechanism normally operable to release the 70 brakes, means for effecting an emergency application of the brakes, means for effecting a service application of the brakes, and a device having connection with the last-mentioned means and adapted to be controlled by the speed of the train to render the last-mentioned means inoperative under certain conditions, and a device adapted to be rendered effective in the operation of the last mentioned means to prevent operation 75 of said mechanism.

32. In train stopping apparatus, means adapted for effecting a service application of the brakes in one position and adapted for effecting an emergency application of the 80 brakes in another position and means tending normally to actuate said first means to emergency position; means holding said second means normally against operation and adapted to release the same, and means adapted to check the operation of said second-named means upon the release of said holding means to hold said first means in service position; said first-mentioned means including a device adapted to be controlled 85 by the speed of the train to render said first-mentioned means inoperative at certain speeds.

In testimony whereof I affix my signature in presence of two witnesses.

DANIEL HERBERT SCHWEYER.
